AUTOMATIC ARROW LOADER

Wiley K. Crowder, Troy, Mich.
(3255 Windcroft, Pontiac, Mich.)

Filed Nov. 21, 1958, Ser. No. 775,565

13 Claims. (Cl. 124—52)

This invention relates to an automatically operable arrow loader for use with a bow. More particularly, the invention is directed to a device adapted for attachment to a conventional bow and having provisions for holding a second arrow in a storage position when a first arrow to be fired is strung onto the bowstring and which device is automatically operable in response to shooting of the first arrow to position the second arrow crosswise of the bow onto the bowstring in position to be fired. By means of this invention it is therefore possible to automatically load a second arrow into shooting position on a bow immediately upon the shooting of a first arrow from the bow. The movable arrow holder for the second arrow is responsive to vibrations such as those caused by firing of the first arrow, which vibrations act as a trigger means for the device, thereby obtaining automatic positioning of the second arrow into shooting position on the bow.

A principal object of the invention is to provide a device for carrying an arrow on a bow and for automatically positioning such arrow crosswise of the bow in response to the shooting of a first arrow from the bow.

A further object of the invention is to provide an automatically operable device for loading an arrow into shooting position on a bow.

A further object of the invention is to provide a means for enabling successive shots from a bow in a minimum amount of time.

Another object of the invention is to provide an arrow loader of the type described which is simple in construction and which is adapted for use with any conventional type of bow.

Other and further objects of the invention will be apparent from the following description and claims and may be understood by reference to the accompanying drawings, of which there are three sheets, which by way of illustration show a preferred embodiment of the invention and what I now consider to be the best mode of applying the principles thereof. Other embodiments of the invention may be used without departing from the scope of the present invention as set forth in the appended claims.

In the drawings:

FIG. 1 is a side elevational view of a bow having the arrow loader of this invention mounted thereon;

FIG. 2 is an enlarged fragmentary side elevational view of the arrow loader;

FIG. 3 is a front elevational view of the device;

FIG. 4 is a horizontal sectional view taken on line 4—4 of FIG. 3;

FIG. 5 is a side elevational view of the loader showing the same just after it has been triggered to position the arrow carried thereby into firing position on the bow;

FIG. 6 is a side elevational view showing the device after the arrow has been correctly positioned and released from the arrow holder; and

FIG. 7 is a fragmentary front elevational view of the device when in the position shown in FIG. 6.

The arrow loader of the present invention is adapted for use with a bow 10 of any conventional design and having a bowstring 12 secured to the ends of the bow in any conventional manner. The arrow loader is indicated in FIG. 1 at 14 and is adapted to hold an arrow 16 in a generally vertical position, while a first arrow 18 is strung on the bow in a conventional manner. The loader 14

2

immediately upon firing of the arrow 18 is adapted to position the arrow 16 into shooting position with the arrow strung on the bowstring 12.

The device includes a supporting bracket in the form of an elongated rod 20 having securing straps 22 and 24 secured to its opposite ends by screws 26. The straps 22 and 24 are provided with a series of aligned apertures 28 by means of which the device may be secured to the bow 10 adjacent the central portion of the bow by suitable screws or bolts 30 extending through two or more of the aligned apertures 28 in each of the straps to position the rod 20 in spaced parallel relation to the bow 10.

A trunnion 32 is slidably and rotatably mounted on the rod 20. The trunnion 32 includes a generally cylindrical wall 34, a top wall 36 and a lower wall 38. The trunnion may be made of a single piece of sheet metal formed as shown and having aligned openings in the upper and lower walls 36 and 38 through which the rod 20 extends. The aperture in the lower wall 38 may be provided with a bushing 40, while the upper wall 36 is provided with a bushing 42 defining an elongated slot 44. The trunnion 32 is rotatable on the rod 20 and slideable axially along the rod in a manner to be described.

An arrow holder 50 is pivotally mounted on the trunnion 32 by a pin 52 extending through opposed vertically extending flanges 54 and 55 formed on the trunnion 32. The arrow holder 50 includes a tubular portion 56 adapted to receive the arrow 16 and a plate portion or web 58 receiving the pivot pin 52. The holder 50 may be made of plastic or resilient metal or of any other material which will enable it to resiliently grip the arrow 16.

The tubular wall portion 34 of the trunnion 32 is provided with a cam slot 60 having a vertical portion 62 and a spiral portion 64. A cam follower 66 is threaded onto a screw 68 secured to and projecting laterally from the rod 20. The cam follower 66 is eccentrically mounted on the screw 68 for a purpose to be described and projects into the cam slot 60 in the trunnion 32 to determine the angular position of the trunnion 32 on the rod 20 as the trunnion slides axially along the rod. The pivot pin 52 has a hook 70 extending laterally therefrom. The upper end 72 of a spring 74 is secured to the hook 70, while the lower end of the spring is connected to an arm 76 having a hooked end 78 and adjustably secured on the lower end 80 of the rod 20 by a screw 81. The spring 74 extends through the interior of the trunnion 32 and through its engagement with the hook 70 urges the arrow holder 50 in a clockwise direction, as viewed in FIGS. 3 and 5, so that the tubular arrow holding portion 56 will be substantially horizontally disposed. This position of the arrow holder 50 is illustrated in FIGS. 6 and 7. The spring 74 also performs the function of pulling the trunnion 32 downwardly toward its lowermost position on the rod 20, which is the position illustrated in FIGS. 6 and 7. In this position of the trunnion the lower bushing 40 engages a stop in the form of a rubber sleeve 82 surrounding the rod 20 just above the lower supporting strap 24.

The pivotal movement of the arrow holder 50 under the influence of spring 74 is limited by engagement of a pin 84 formed on the end of the plate portion 58 of the holder 50 with the vertically extending wall 86 forming a part of the trunnion 32.

The arrow loader is loaded by placing an arrow 16 within the tubular arrow holding element 56 and then pivoting the arrow holder 50 in a counterclockwise direction, as viewed in FIGS. 3 and 5, until the arrow 16 is substantially vertically disposed. This pivoting of the holder 50 will also pivot the hook 70 to the position shown in FIGS. 2 and 3. The trunnion 32 is then slid upwardly along the rod 20 to the position shown in FIGS. 2 and 3, the slot 60 and cam follower 66 effecting rotation

of the trunnion through about 90° as the trunnion is raised to its upper position. The rod 20 is provided adjacent its upper end with a detent 90 in the form of a lug projecting laterally from the rod. The elongated slot 44 in the upper bushing 42 and the top wall 36 of the trunnion 32 is sufficiently large to enable the bushing to pass upwardly over the detent lug 90. The upper end of the hook 70 will rest against the outer side of the upper supporting strap 22. The direction of the force of the spring 74 acting through the hook 70 is such that the upper end of the trunnion 32 will be forced laterally to cause the upper bushing 42 to seat on the detent lug 90 to hold the trunnion and arrow holder in the upper or loaded position thereof. This is the storage position of the second arrow 16, and the bow may be used in a conventional manner with the arrow 18 at this time.

When the first arrow 18 is shot from the bow 10, the vibrations resulting from release of the bowstring 12 will be sufficient to jar the upper end of the trunnion 32 sufficiently to cause the bushing 42 to slip off of the detent lug 90, whereupon the spring 74 will pull the trunnion downwardly while rotating the same through about 90° along the rod 20 toward the position shown in FIG. 5. The rod 20 is provided with a cam lug 92 and a second detent lug 94 disposed a short distance below the lug 92 and on the opposite side of the rod from the cam lug 92. As the detent lug 90 is disengaged, the trunnion will drop vertically while rotating around the rod 20 by means of the engagement of the spiral slot 64 in the trunnion and the cam follower 66 on the rod. The cam lug 92 will be engaged by the forward edge of the elongated slot 44 as the trunnion descends to shift the upper end of the trunnion forwardly, thereby causing the trailing edge of the bushing 42 to seat upon the detent lug 94 as shown in FIG. 5. The spring 74 will also pivot the arrow holder 50 in a clockwise direction at such time and the device is shown in FIG. 5 after the trunnion has seated upon the detent lug 94 and while the holder 50 is being pivoted to bring the arrow 16 into operative position on the bow 10. The spiral portion 64 of the slot 60 in the trunnion will effect about 90° rotation of the trunnion and the arrow holder carried thereby to bring the arrow into the correct position along the left-hand side of the bow 10. As the arrow 16 swings downwardly, the notch 96 in the end thereof will engage the bowstring. The arrow will remain within the tubular portion 56 of the holder 50 at such time. As soon as the arrow 16 is strung onto the bow in the manner described the arrow may be drawn back in the customary manner, which will result in the trunnion 32 being tilted slightly toward the bow to disengage the bushing 42 from the detent 94, whereupon the trunnion will drop further along the rod 20 to the position shown in FIGS. 6 and 7 in which the lower bushing 40 engages the stop 82. The arrow 16 may be easily detached from the holder 50 during this movement of the trunnion since the arrow will then be positioned just above the hand which grips the bow. As the trunnion drops to the position shown in FIG. 6, the arrow will be lifted out of the holder and is then in position to be fired. The correct position of the arrow 16 within the arrow holder to insure that the notched end of the arrow engages the bowstring 12 when the device is actuated can readily be determined when the arrow is inserted into the holder.

It will be seen that the arrow loader is capable of being used with bows of different sizes and of any conventional design. The tension of the spring 74 may be adjusted to give proper functioning of the device by adjusting the angular position of the arm 76. The eccentric mounting of the cam follower 66 on the screw 68 enables the cam follower to be turned on the screw to give the proper clearance of the follower 66 within the slot 60 to insure free sliding and rotative movement of the trunnion on the rod 20. Since the force of the spring 74 is exerted along a line passing very close to the axis of the pivot pin 52, very little force is necessary to jar the trunnion out of

engagement with the detent lug 90 to trigger the device. The adjustments previously referred to can be utilized to enable operation of the loader by forces such as the vibrations caused by release of the bowstring upon shooting an arrow so that the device is automatically operable to position a second arrow into shooting position.

A locking arm 100 is pivoted on a horizontal axis to the rod 20 above the lug 90 and is employed as a safety device to prevent accidental triggering and actuation of the automatic loader. When the trunnion is in its elevated or loaded position shown in FIGS. 2 and 3, the locking arm 100 may be swung downwardly to engage a flat 102 formed on the top wall 36 of the trunnion and thereby prevent the trunnion from moving off of the detent lug 90.

The automatic arrow loader described herein enables two shots to be obtained in very rapid succession since shooting of the first arrow triggers the device to string the second arrow on the bowstring and drawing back the second arrow in the customary manner automatically disengages the arrow from the arrow holder.

While I have illustrated and described a preferred embodiment of my invention, it is understood that this is capable of modification, and I therefore do not wish to be limited to the precise details set forth but desire to avail myself of such changes and alterations as fall within the purview of the following claims.

I claim:

1. An automatically operable arrow loader for use with a bow, comprising an arrow holder, and means movably supporting said holder on the bow for movement between a first position in which an arrow carried by said holder is disposed generally parallel to the bow, and a second position in which the arrow is disposed crosswise of the bow, means for biasing said holder toward said second position, and detent means holding said arrow holder in said first position.

2. An arrow loader according to claim 1 wherein said detent means is responsive to vibrations such as caused by shooting a first arrow to release said holder for movement to said second position.

3. An arrow loader according to claim 1 wherein said means movably supporting said arrow holder includes a supporting bracket and means adapted to secure said bracket to said bow, said arrow holder being mounted on said bracket for movement, simultaneously; in a direction parallel to the bow; in an arc from one side of the bow to the other; and pivotal movement on an axis normal to the bow.

4. An automatically operable arrow loader for use with a bow, comprising an arrow holder, and means adapted for movably supporting said holder on the bow for movement between a first position in which an arrow carried by said holder is disposed at one side of and generally parallel to the bow, a second position in which the arrow is disposed crosswise of and on the other side of the bow, and a third position in which the arrow is disengaged from said arrow holder, and means for biasing said holder toward said third position, and first and second detent means for holding said arrow holder in said first and second positions.

5. An arrow loader according to claim 4 wherein said first detent means is responsive to vibrations caused by shooting a first arrow from the bow to release said arrow holder for movement from said first to said second position, and wherein said second detent means is responsive to drawing of the arrow when in said second position to release said holder for movement from said second to said third position.

6. An automatic arrow loader for use with a bow, comprising a supporting bracket adapted for attachment to a bow, an arrow holder movably supported on said bracket, and means constraining said holder for movement on said bracket between a first position in which an arrow carried by said holder is disposed generally parallel to the bow, and a second position in which the arrow is disposed cross-

wise of the bow and lies in a plane containing the bowstring, said supporting bracket including a rod disposed in spaced, generally parallel relation to said bow, a trunnion slidably and rotatably carried by said rod, said arrow holder being pivotally mounted on said trunnion, spring means urging said holder and trunnion toward said second position, and detent means for releasably holding said holder and trunnion in said first position.

7. An automatically operable arrow loader for use with a bow, comprising an arrow holder movably supported on the bow, spring means urging said arrow holder to a position in which an arrow carried by said holder is strung on the bowstring in position to be fired, said holder being movable into a storage position in which the arrow is disposed generally parallel to the bow, and detent means for holding said arrow holder in said storage position, said detent means being responsive to vibrations such as caused by shooting a first arrow to release said holder for movement to string the arrow carried by the holder on the bowstring.

8. An automatically operable arrow loader for use with a bow, comprising a rod, means for supporting said rod from the bow, a trunnion slidably and rotatably carried by said rod, an arrow holder pivotally mounted on said trunnion, spring means urging said arrow holder and trunnion to a position in which the arrow carried by said holder is disposed crosswise of the bow in position to be fired, said holder and trunnion being movable into a storage position in which the arrow is disposed generally parallel to the bow, and detent means for holding said arrow holder and trunnion in said storage position, said detent means being responsive to vibrations such as caused by shooting a first arrow to release said trunnion and holder for movement by said spring means.

9. An arrow loader according to claim 8 including a safety lock for preventing release of said trunnion from said storage position.

10. An arrow loader according to claim 8 including a second detent for limiting movement of said trunnion by said spring means, said trunnion being movable with the arrow as the arrow is drawn back so as to disengage said trunnion from said second detent for further movement by said spring means thereby to disengage the arrow from said holder.

11. An automatic arrow loader for use with a bow, comprising a rod, means for securing the rod to a bow in spaced generally parallel relation to the bow, a trunnion slidably and rotatably carried by said rod, an arrow holder pivotally mounted on said trunnion on an axis normal to said rod, spring means urging said arrow holder to a position on the trunnion in which an arrow carried by said holder is disposed crosswise of the bow, said spring means also urging said trunnion axially along said rod in one direction, said holder being pivotable on said trunnion and the latter being movable along said rod in the opposite direction into a storage position in which the arrow is disposed generally parallel to and at one side of the bow, a first detent on said rod for holding said trunnion and arrow holder in said storage position, a second detent on said rod, said first detent being responsive to vibrations such as caused by shooting a first

arrow from the bow to release said trunnion and holder for pivotal movement of said holder to said crosswise position and axial movement of said trunnion into engagement with said second detent, cam means on said rod and trunnion for effecting rotative movement of said trunnion as the same moves from said storage position into engagement with said second detent, thereby to string the arrow carried by the holder on the bowstring with said arrow disposed crosswise and on the other side of the bow, said trunnion being movable with the arrow as the arrow is drawn back to disengage said trunnion from said second detent to effect further axial movement of said trunnion in said one direction thereby to disengage said arrow from said holder.

12. An automatic arrow loader for use with a bow, comprising a supporting bracket adapted to be secured to a bow, a trunnion movably mounted on said bracket, an arrow holder pivotally mounted on said trunnion, said holder being pivotable on said trunnion and the latter being movable on said bracket into a storage position in which the arrow is disposed generally parallel to and at one side of the bow, a first detent for holding said trunnion and arrow holder in said storage position, a second detent, said first detent being responsive to vibrations such as caused by shooting a first arrow to release said trunnion and holder for pivotal movement of said holder and movement of said trunnion on said bracket into engagement with said second detent thereby to string the arrow carried by the holder on the bowstring with said arrow disposed crosswise and on the other side of the bow, said trunnion being disengaged from said second detent as the arrow is drawn back to effect further movement of said trunnion on said bracket thereby to disengage said arrow from said holder.

13. An automatic arrow loader for use with a bow, comprising a supporting bracket adapted to be secured to a bow, an arrow holder movably mounted on said bracket, spring means urging said arrow holder to a position on the bracket in which an arrow carried by said holder is disposed crosswise of the bow, said holder being movable against said spring means into a storage position in which the arrow is disposed generally parallel to the bow, a first detent on said bracket for holding said arrow holder in said storage position, a second detent on said bracket, said first detent being responsive to vibrations caused by shooting a first arrow to release said holder for movement to said crosswise position and into engagement with said second detent, thereby to string the arrow carried by the holder on the bowstring with said arrow disposed crosswise of the bow, said holder being disengaged from said second detent as the arrow is drawn back to effect further movement of said holder thereby to disengage said arrow from said holder.
